UNITED STATES PATENT OFFICE

150,546

DESIGN FOR AN EARRING

Marcel Boucher, New York, N. Y.

Application July 29, 1946, Serial No. 132,067

Term of patent 3½ years

(Cl. D45—9)

To all whom it may concern:

Be it known that I, Marcel Boucher, a citizen of the United States, residing in New York City, in the county of New York and State of New York, have invented a new, original, and ornamental Design for an Earring, of which the following is a specification, reference being had to the accompanying drawing, forming part thereof.

Fig. 1 is the front view of an earring showing my design, and

Fig. 2 is the edge view thereof.

I claim:

The ornamental design for an earring, substantially as shown.

MARCEL BOUCHER.
